DESIGN FOR A HEADSTOCK FOR MACHINE TOOLS

Milburn A. Hollengreen and Charles R. Mentzer,
Waynesboro, Pa., assignors to Landis Tool Com-
pany, Waynesboro, Pa.

Application December 16, 1938, Serial No. 81,830

Term of patent 14 years

To all whom it may concern:

Be it known that we, Milburn A. Hollengreen and Charles R. Mentzer, citizens of the United States, residing at Waynesboro, in the county of Franklin and State of Pennsylvania, have invented a new, original, and ornamental Design for a Headstock for Machine Tools, of which the following is a specification, reference being had to the accompanying drawing, forming part thereof.

Figure 1 is a front perspective view of a headstock for machine tools showing our new design; and

Figure 2 is a rear perspective view thereof.

We claim:

The ornamental design for a headstock for machine tools, substantially as shown.

MILBURN A. HOLLOWGREEN,
CHARLES R. MENTZER.
